DUAL OUTLET EXHAUST SYSTEM

BRIEF SUMMARY OF THE INVENTION

It is the purpose of the invention to provide a highly effective, minimum cost exhaust gas silencing system for internal combustion engines.

The invention accomplishes this object by means of a system that has a single muffler that discharges into two flow balanced branches that convey the gas to the system outlet points.

DESCRIPTION OF THE DRAWINGS

FIG. 1 is a perspective, schematic view of an exhaust system embodying the invention;

FIG. 2 is an enlarged view of a portion of the system of FIG. 1, broken away to show a modification;

FIG. 3 is an enlarged cross section through one of the outlet sections showing a means for forming a flow balancing restriction therein;

FIG. 4 is a view similar to FIG. 1 showing another embodiment of the invention; and

FIG. 5 is a view similar to FIG. 1 and 4 showing another embodiment of the invention.

DESCRIPTION OF THE INVENTION

The internal combustion engine 1 typifies a high powered V-8 unit used in many modern automobiles with dual exhaust manifolds 3 and 5. The exhaust system 7 comprises dual, uniform diameter exhaust pipes 9 and 11 connected to the manifolds 3 and 5, respectively, and joined together in a Y point 13 so that their flow is combined in a single exhaust pipe section 15 that leads to the inlet 17 of a single exhaust gas muffler 19. After silencing in the muffler 19 gases leaving the muffler outlet 21 enter a single tailpipe section 23 that is connected thereto. A short distance from the outlet 21, the uniform diameter tailpipe member 25 that provides section 23 has an opening formed in its wall and a branch uniform diameter tailpipe member 27 is welded to member 25 around the opening in a Y joint 29 so that the system 7 has a dual tailpipe structure, i.e., branch tailpipe 27 and the section 31 of tailpipe member 25 which is downstream from the Y joint 29.

In the system illustrated the muffler 19 is located substantially to the right of the center line of the vehicle so that in order that the respective outlets 33 and 35 of the sections 27 and 31 be symmetrically located at the rear of the vehicle on opposite sides of the center line, the section 27 has a portion 37 that diverges from the tailpipe member 25. The sections 27 and 31 have transversely aligned kick-up sections or arches 39 and 41, respectively, to go over the rear axle of the vehicle and these merge into end sections 43 and 45, respectively, that terminate in the outlets 33 and 35.

It is desired that the flow through the dual tailpipe sections 27 and 31 be balanced or equalized and appropriate means is employed, where necessary, to achieve this balance. In the structure illustrated, the section 31 is somewhat shorter in length than section 27 and also in line with flow from the muffler outlet 21 and, hence, in the absence of flow balancing means would present less resistance to flow than the branch 27. As a balancing means, therefore, the branch 27 may be larger in cross section or diameter than the section 31. Alternatively, as shown in FIG. 2, the section 31 may contain a fixed restrictor or orifice means 47 in the form of a Z-shaped tubular insert to substantially equalize its re-

sistance with that of the section 27. A further alternative is shown in FIG. 3 where pinch sections 48 are used to reduce the inner diameter of section 31.

The operation of the system 7 is apparent. The system has the advantage of presenting the appearance of a dual exhaust system since the single system components are located beneath the automobile and out of sight. The use of a single muffler instead of two mufflers causes the muffler to operate at higher temperature level than the mufflers of a true dual system and this promotes a longer muffler life.

An important advantage of the dual outlet arrangement of the invention is its reduction in the sound level of gas leaving the muffler 19. The combined areas of branches 27 and 31 substantially exceeds the area of muffler outlet 21 and that of the upstream gas passages including section 23 and the gas velocity is therefore substantially reduced in the dual tailpipe portion of the system. This diminishes the "air rush" effect and the noise associated with it and thereby lowers the sound level at the rear of the system 7.

While it is preferred that a single inlet muffler, as illustrated, be used in systems of the invention, it is apparent that benefits of the invention are also obtained if the muffler is of a dual inlet, single outlet type in which case the exhaust pipes 9 and 11 would not merge but would feed directly into two muffler inlets. Further, as seen in FIG. 4, the muffler may have a single inlet and this together with small diameter of pipes inside the muffler may result in a high gas velocity and the possibility of air rush noise which the balanced dual tailpipe arrangement of FIG. 4 overcomes.

In FIG. 4, the engine 101 has only a single exhaust manifold 103 discharging into a single exhaust pipe 105 that leads to the inlet 107 of muffler 109. The muffler 109 has a single outlet 111 emptying into a tailpipe member 113 (similar to member 25) that includes a uniform diameter inlet section 115 connected to the outlet 111. The member 113 has a tailpipe section 117 that is substantially in line with outlet 111 and a hole in its sidewall is covered to form a Y joint 119 by branch tailpipe section 121 which is welded to it. As in the case of member 25 the section 117 (like section 31) presents less resistance to flow and flow balancing means in the form of a reduced diameter portion 123 of pipe section 117 is provided to substantially equalize the resistance of the two sides 117 and 121.

In FIG. 5, a dual manifold engine 201 discharges exhaust gases into exhaust pipes 203 and 205 which are connected together in a Y joint 207 to form a single exhaust pipe section 209 that is connected to the inlet bushing 211 of muffler 213. The muffler is of the dual outlet type with outlets 215 and 217 connected to two tailpipes 219 and 221 of unequal length. Suitable flow balancing means are incorporated in one or both of the pipes to equalize flow and resistance, this being illustrated as orifice members 223 and 225, respectively, in pipes 219 and 221.

Thus, it is apparent that the invention may be used with any internal combustion engine to reduce exhaust noise of various types and that it is particularly useful in systems wherein there is a muffler having a single inlet bushing. Modifications in the specific details illustrated may be made without departing from the spirit and scope of the invention.

I claim:

1. An exhaust system for internal combustion engines comprising a single muffler having outlet means, a single tailpipe section connected to and receiving all gas from said outlet means, and a pair of tailpipe sections connected to and receiving all gas from said single tailpipe section, the combined cross sectional area of the pair of sections being greater than the cross sectional area of the single tailpipe section, and means for substantially equalizing flow in the pair of tailpipe sections, said means comprising a reduced diameter cross section in one of the pair of tailpipe sections acting as a flow restricting orifice.

2. An exhaust system for internal combustion engines comprising a single muffler having outlet means, a single tailpipe section connected to and receiving all gas from said outlet means, and a pair of tailpipe sections connected to and receiving all gas from said single tailpipe section, the combined cross sectional area of the pair of sections being greater than the cross sectional area of the single tailpipe section, and means for substantially equalizing flow in the pair of tailpipe sections, one of said pair of tailpipe sections being larger in cross section than the other and the difference in cross section between two sections comprising said means.

3. A dual type exhaust system for an internal combustion engine having two exhaust manifolds comprising a pair of exhaust pipes connected one to each of said manifolds, a single muffler, means connecting both exhaust pipes to said muffler, said muffler having a single outlet, a single tailpipe section connected to and receiving all gas from said outlet, a pair of tailpipe sections connected to and receiving all gas from said single tailpipe section, the combined cross sectional area of the pair of sections being greater than the cross sectional area of the single tailpipe section and the flow through the respective sections of said pair being substantially equal, said muffler having a single inlet and said means comprising a common exhaust pipe connected to and receiving gas from both said exhaust pipes and connected to said single inlet.

4. In an exhaust system for an internal combustion engine, a single muffler having inlet means and outlet means, exhaust pipe means connecting the engine to the inlet means, tailpipe means connected to and receiving all gas from said outlet means, said tailpipe means including a pair of tailpipe sections connected to and receiving all gas from said muffler, and means for substantially equalizing flow in the pair of tailpipe sections, said outlet means comprising two separate out-

lets connected respectively to said tailpipe sections, at least one of said tailpipe sections including flow restricting means to serve as said flow equalizing means.

5. An exhaust system for internal combustion engines comprising a single muffler having outlet means, a single tailpipe section connected to and receiving all gas from said outlet means, and a pair of tailpipe sections connected to and receiving all gas from said single tailpipe section, the combined cross sectional area of the pair of sections being greater than the cross sectional area of the single tailpipe section, one of said tailpipe sections being substantially longer than the other, and means for substantially equalizing flow in the pair of tailpipe sections.

15 6. A dual type exhaust system for an internal combustion engine having two exhaust manifolds comprising a pair of exhaust pipes connected one to each of said manifolds, a single muffler, means connecting both exhaust pipes to said muffler, said muffler having a single outlet, a single tailpipe section connected to and receiving all gas from said outlet, a pair of tailpipe sections connected to and receiving all gas from said single tailpipe section, one of said pair of tailpipe sections being substantially longer than the other, the combined cross sectional area of said pair of tailpipe sections being greater than the cross sectional area of the single tailpipe section, and flow restriction means in one of the tailpipe sections whereby the flow through the respective sections of said pair are substantially equal.

20 7. A dual type exhaust system comprising a single rectangular muffler having a single tubular inlet at one end and a single tubular outlet at the other end, a single exhaust pipe connected to said inlet and a single tailpipe connected to said outlet, a pair of exhaust pipes connected in a Y joint to said single exhaust pipe, and a pair of tailpipes connected in a Y joint to said single tailpipe, the combined areas of said pair of tailpipes being larger than the area of said single tailpipe.

25 8. In an exhaust system for an internal combustion engine, a single muffler having inlet means and outlet means, exhaust pipe means connecting the engine to the inlet means, tailpipe means connected to and receiving all gas from said outlet means, said tailpipe means including a pair of tailpipe sections connected to and receiving all gas from said muffler, and restriction means in one of the tailpipe sections for substantially equalizing flow in the pair of tailpipe sections.
